UNITED STATES PATENT OFFICE.

AUGUST FURST, OF CORNING, KANSAS.

STRAW-STACKER.

SPECIFICATION forming part of Letters Patent No. 376,873, dated January 24, 1888.

Application filed April 21, 1887. Serial No. 235,689. (No model.)

To all whom it may concern.

Be it known that I, AUGUST FURST, a citizen of the United States, residing at Corning, in the county of Nemaha and State of Kansas, 5 have invented a new and useful Improvement in Straw-Stackers, of which the following is a specification.

My invention relates to an improvement in straw-stackers; and it consists in the construction and arrangement of the parts of the same, which will be more fully hereinafter described, and pointed out in the claims.

The object of my invention is to provide an improved straw-stacker which is simple and 15 effective in its construction and operation, strong and durable, easily handled and readily understood, convenient and accessible at all times, positive in its results, and comparatively inexpensive in its manufacture. I attain this object by the construction illustrated 20 in the accompanying drawings, wherein like letters of reference indicate similar parts in the several views, and in which—

Figure 1 is a side elevation of my improved straw-stacker, showing the traveling carriage or truck in full lines and ready to be loaded, and in dotted lines at the upper end of the stacker in the act of dumping the load therefrom. Fig. 2 is an end elevation with the 25 traveling carriage or truck on the tilting or dumping frame at the upper end of the stacker. Fig. 3 is a top plan view of my improved stacker with the truck in position thereon. Fig. 4 is a detail perspective view of the elevating truck or carriage.

A indicates the base frame-work or beams, which has two forward standards or uprights, A', which are united and braced by cross-beams A² and by tie-braces a a. To the rear 40 portion of the base-frame A the inclined beams B are secured, which are connected to inclined beams B', which are of greater inclination than the said beams B and extend upwardly and are secured to the top portion of the uprights A' A'. The rear portion of the incline B is in close proximity to the ground, while the incline B' extends up to a considerable elevation for the formation of the stack. These inclines are provided with suitable track-rails, b b, 45 which are suitably secured therein, and are of the desired form of construction. The upper part of the inclines B' is provided with a tilt-

ing table, B², which forms a continuation of the inclined frame B', and is trunnioned or pivoted in the uprights A'. To the central portion of this frame B² a beam or metallic rod, B³, is secured and projects slightly in the rear thereof, and has a weight, B⁴, connected to its rear portion by means of a suitable attaching chain or rope. This weight B⁴ is sufficiently 55 heavy to overbalance the weight of the tilting frame and cause the same to return to its normal position in connection with the inclined frame B'. This frame or tilting table B² is also provided with track-irons, which engage with the track b, mounted in the incline B'. Upon the track-irons b of the incline a suitable truck, C, is adapted to travel and engage therewith, and has a tilting gate, C', mounted in the rear portion thereof. This gate C' is constructed 60 of three uprights, c c, the lower ends of which are slotted and engage with pins mounted in the upper platform of the truck. The said gate is adapted to be raised slightly on the pins just described and tilted down backward 65 from the truck onto the ground, and thereby greatly facilitate the loading of said truck with a quantity of hay or straw.

In the upper portion of the standards A' suitable sheaves or pulleys, 1 1, are mounted 70 and secured on the sides thereof, while in the front lower portion of said standards sheaves or pulleys 2 2 are also secured. Through the sheaves or pulleys a draft-rope, D, is adapted to pass, and extends downward and is secured 75 at its two ends to the rear portion of the truck C. This draft-rope D is adapted to draw the said truck C up the inclines B and B' when the said truck shall have been loaded and it is desired to dump the quantity of hay or straw 80 thereon on top of the stack and off from the forward end of the said uprights A A'. The draft-rope D extends outward from one side of the stacker and has an attaching-loop, d, secured to its outer end, to which horse-power 85 may be applied for drawing the truck upward on the inclines B and B'. When the truck C shall have been drawn upward over the inclines B and B' and to gradually ride over onto the tilting table B², and when the said truck has 90 reached the extreme forward end of the said tilting table, the weight thereof, and the combination with the weight of the load of straw carried by said truck, will overcome the effect 95 100

of the weight B^4 , secured to the rear portion of the said tilting table, as described, and the said table B^2 will tilt forward, dumping the contents or hay carried upon the truck C over the forward end of the stacker. When the said table B tilts downward in the act of dumping, the forward ends thereof strike against projecting beams B^5 B^6 , extending outward from the forward end of the stacker, and which are adapted to prevent the said table from tilting too far, being so arranged that when the said table strikes thereagainst it will be in a sufficiently-inclined position to cause a dumping of the contents or straw carried by the truck C . Slightly in the rear of the middle portion of the said table B^2 , and on the inner sides of the track-beams thereof, headed pins or bolts b^2 project outwardly therefrom, and are engaged by depending recessed plates c' , secured to the under part of the carriage C , and in a similar manner the under portion of the frame-work of the said carriage C is provided with studs or pins c^3 , which are engaged by recessed plates b^3 , projecting upwardly at right angles from the said tilting table B^2 . When the carriage or truck C rides upon the tilting table B^2 , the several plates and projecting pins of the studs engage with each other, and the said carriage is held in contact with the tilting table and prevented from running over the edge thereof or tilting therefrom when dumped or tilted downward by the action of the said frame B^2 . When the load which has been carried up the inclines B and B' by the carriage C has been dumped, as described, the draft-rope is slackened by reversing the movement of the power attached thereto, thereby lowering the car or carriage C down the inclines B and B' to receive another load of hay or straw, and when the said carriage reaches the extreme lower end of the inclines B the depending plates c^2 thereof engage with projecting pins b^4 , secured in the rear portion of the said inclines B and the carriage C , and are thereby prevented from becoming disengaged from the track b .

The central upright, c , of the tilting gate C' of the carriage C , is provided with a strap-loop, c^4 , to which an operating-cord may be attached for lowering the said gate when it shall have reached the lower portion of the incline A , without the necessity of coming down from the top of the load of hay or straw which may be at the time adapted to be loaded upon the carriage and stack from the end of the stacker.

It is obvious that the construction of the device entire may be regulated and adjusted to suit the height of the stack required; and it is obvious, further, that the truck C may be used to advantage in the elevation of heavy bodies other than hay or straw.

Many minor changes in the construction and arrangement of the parts may be made and substituted for those shown and described without in the least departing from the nature and principle of my invention.

Having thus described my invention, I claim—

1. In a hay-stacker, the combination of a supporting frame-work, the two inclines B and B' , the incline B' of which is arranged at a greater angle of inclination than the incline B , the tilting table arranged at the upper part of said incline and trunnioned or pivoted in the uprights A' , track-irons b , mounted in the several parts, a truck or carriage, C , having a tilting gate, C' , traveling and adapted to ascend said inclines, the sheaves or pulleys arranged and mounted upon the uprights A' , as set forth, the draft-ropes connected to the carriage and passing through the said sheaves or pulleys, and the projecting beams B^5 , substantially as described.

2. In a hay-stacker, the combination of the supporting frame, the inclines mounted in connection therewith, having track-irons secured thereto, the tilting table at the upper forward end thereof, having suitable stops or pins and recessed plates, the truck or carriage traveling on said track-irons and provided with a drop-gate, studs or pins and recessed plates secured to the under sides of the frame-work of the said truck or carriage and adapted to engage with the plates and pins in the tilting table, the projecting beams B^5 , and the draft-rope D , connected to the said truck or carriage and passing through the sheaves or pulleys 1 1 and 2 2, arranged in the forward part of the frame-work, substantially as described.

3. In a hay-stacker, the combination, with the supporting frame-work, of the inclines mounted thereupon, having a tilting table in the upper portion thereof, a truck or carriage moving on the track-irons mounted in connection with said inclines and connected to draft-ropes, operated as described, and a movable gate mounted in the rear portion of said truck or carriage and adapted to be tilted downward in loading the said carriage with hay or straw, and to be raised in a vertical position when the said truck or carriage has been loaded, substantially as described.

In testimony that I claim the foregoing as my own I have hereto affixed my signature in presence of two witnesses.

AUGUST FURST.
